AUTOMATIC TELEPHONE SYSTEM

Morris E. Griffins, Western Springs, Ill., assignor,
by mesne assignments, to Associated Electric
Laboratories, Inc., Chicago, Ill., a corporation
of Delaware

Application July 12, 1935, Serial No. 30,957

13 Claims. (Cl. 179—175.2)

The present invention relates in general to automatic telephone systems, and more in particular to the equipment which is provided to enable the wire chief to test the lines in such systems. 5 This equipment may comprise a test circuit which includes the instruments and keys required to perform the tests, one or more test distributors, and a connector for each group of lines. The test circuit is connected to any desired line by operating a test distributor to select the group in which the line is located and by then operating the test connector in that group to select the particular line to be tested. If there are more than one-hundred groups of lines, test connector selectors may 10 be inserted between the test distributors and the test connectors. The U. S. patent to Crocker, No. 1,576,723, shows a complete testing system of this character.

The system disclosed in the Crocker patent is 20 intended for use in a single exchange and as a practical matter is limited to use in a single exchange, not only because of the number of conductors required between the test distributors and test connectors (six conductors), but also 25 because the resistance of certain of these conductors would be too high to enable the system to operate properly if it were attempted to give the test distributors in one office or exchange direct access to test connectors in a distant office.

30 Situations frequently arise, however, where centralized testing is desired, that is, it is desired to have the wire chief in one office test lines in an outlying office as well as in his own office. The usual method of handling this situation is to provide the wire chief with a direct test trunk extending to the outlying office and terminating therein in a test distributor having access to test connectors. This amounts to a duplication of the Crocker system, separate test trunks and test 35 switches being provided for each office.

40 While the foregoing arrangement works all right it is objectionable in many situations because it requires the wire chief to select a test trunk in accordance with the office in which the line to be tested is located, and because he is required to omit the office designation in dialling the number of the line, which leads to confusion. This latter objection is particularly important where the test switch train is used by the toll operators for verification purposes, it being desirable that the toll operators should dial the directory numbers and not have to omit any digits. There are other objections which need not be gone into, and a demand has arisen, therefore, for a 45 test train which can be used by the wire chief or

toll operator to gain access to subscribers' lines either in the main office or in an outlying office by dialling the regular telephone numbers of such lines.

5 As an example of where such an improved test train may be used, a telephone system may be considered which comprises several different offices interconnected by trunk lines and forming a network giving service to a fair sized city. If there are less than ten offices a five digit numbering system may be employed, the first digit of any number serving to designate the office while the other four digits identify the line in the office. There are numerous telephone systems of this type 10 installed in the United States and other countries 15 and the system is therefore well known.

According to the present invention one of the offices in the system is selected as a testing office and there the wire chief's desk is located. The toll board may be at the same point if the test 20 train is to be used for verification. From the wire chief's test desk four conductor test trunks extend to test distributors. These test distributors, when used to connect with a line in the testing office, respond to two digits and have access to test connector selectors. These latter respond to one digit 25 and have access to test connectors, which respond to two digits and make the final line selection. Thus the complete switch train used to connect with a line in the testing office comprises a test distributor, a test connector selector, and a test connector, requiring five digits for their operation. Such a test switch train is shown complete 30 in the Crocker patent hereinbefore referred to. The present invention contemplates using test connector selectors and test connectors of the type shown in the Crocker patent. The test distributor, however, is different from the test distributor there shown.

45 Now, in order to enable the wire chief to connect with the lines in other offices the test distributor is also given access to test trunk lines extending to such other offices. Suppose there are three offices, for instance, the testing office and two other offices. The testing office may have numbers beginning with the digit two, while the other offices may have numbers beginning with the digits three and four, respectively. Then in the second level of the test distributors access is had to local test connector selectors, the 50 test distributors responding to two digits as previously explained. In the third level of the test distributors access is had to a group of four conductor test trunks leading to test distributors in the No. 3 office. These test distributors may 55

be of the type shown in the Crocker patent, or of the type shown in the instant case, and have access to test connectors of the type shown in the Crocker patent. In the fourth level of the 5 test distributors in the testing office, the No. 2 office, access is had to four conductor test trunks leading to test distributors in the No. 4 office. The arrangement in the No. 4 office is the same as in the No. 3 office, comprising test distribu- 10 tors and test connectors.

It will be understood now that the test distributors in the testing office must function differently in setting up connections to lines in the No. 3 or No. 4 office than they do in setting up 15 connections to lines in the No. 2 office. In the case of a connection completed within the No. 2 office, the test distributor used responds to two digits and selects a particular test connector selector. In the case of a connection to a line 20 in one of the other offices, however, the test distributor used responds only to one digit, the office selecting digit, and is then given an automatic hunting movement to select an idle inter- 25 office test trunk. One feature of the invention, therefore, is a combined one and two digit test distributor.

The four conductor test trunks outgoing from the wire chief's desk, and also the four conductor inter-office test trunks, each comprise two 30 operating conductors and two test conductors. The former are used to operate and maintain the switch train, while the latter are connected to the subscriber's line by operation of the train and are used for testing purposes. Now in testing lines the wire chief must be able to drop the bridge cut-off relay of a line undergoing test so as to be able to make an inward test of the 35 line, that is, a test toward the switchboard. The bridge cut-off relay is dropped or deenergizes by 40 imposing a certain control condition on the two operating conductors of the test trunk. Another requirement is that the wire chief be able to release the test connector in use without 45 releasing the test distributor. The release of the test connector is brought about by imposing a different control condition on the two operating conductors. A further feature of the invention, therefore, is a test distributor which includes 50 means for relaying or repeating certain control conditions, commonly referred to as B. C. O. and connector release, over an inter-office test trunk to a test distributor in a distant office.

The foregoing and other features will be described hereinafter with reference to the accompanying drawing, which shows diagrammatically 55 sufficient of the equipment and circuits involved to enable the invention to be understood.

Referring to the drawing, the rectangle TC at the left of the drawing indicates a wire chief's 60 test circuit, which may be the same as the one disclosed in the Crocker patent previously mentioned. The drawing shows only so much of the test circuit equipment as is involved in the description of the instant invention. This com- 65 prises a calling device CD, and two keys labelled Conn. Release and B. C. O. for placing the control conditions hereinbefore referred to on the operating conductors of the test trunk.

Outgoing from the wire chief's desk there is 70 a four conductor test trunk comprising operating conductors 3 and 4 and test conductors 5 and 6. The test circuit may be connected to the test trunk by any well known means (not shown), such as a key, or plug and jack.

75 The test trunk extends to a test distributor,

indicated by the reference character TD. This test distributor is a Strowger vertical and rotary switch of well known mechanical construction. The circuit is novel and will be fully described hereinafter.

The test distributor TD has six wipers 23-28. On the second level these wipers have access to six conductor trunks extending to test connector selectors, as previously explained. One such trunk, comprising conductors 80-85, is indicated 10 in the drawing. This trunk extends to a test connector selector, and the latter has access to test connectors. Since these switches may be the same as those disclosed in the Crocker patent they are not shown herein.

On the third level the test distributor TD has access to four conductor test trunks extending to the No. 3 office. One of these trunks is indicated in the drawing and comprises conductors 86-89. This trunk extends to the No. 3 office 20 and there terminates in a test distributor which may be the same as the distributor TD or which may be the same as the test distributor shown in the Crocker patent. In any event, the test distributors in the No. 3 office have access to 25 test connectors of the same type as those previously referred to, i. e., like those in the Crocker patent. Under the circumstances it has not been considered necessary to show the test distributor and test connector used in the No. 3 office.

It will be assumed that the wire chief desires to connect his test circuit with a local subscriber's line in the No. 2 office for the purpose of testing such line. In order to accomplish this, the wire chief connects the test circuit to 35 an idle test distributor by means of a key or plug and jack arrangement, as previously mentioned, and then operates his calling device in accordance with the digits in the subscriber's telephone number. It may be assumed that this 40 telephone number is 21456.

Assuming that the test circuit TC and the test distributor TD are used for setting up the connection, when the test circuit is connected to the test distributor the line relays 8 and 10 of the 45 test distributor will pull up over the two operating conductors 3 and 4 in series, these conductors being bridged by the calling device CD in the test circuit. Upon energizing, relay 8 closes a circuit via 31 and 49 for the slow acting re- 50 lease relay 11. Relay 10 also closes a circuit for relay 11 at 35. Upon energizing, relay 11 prepares the impulsing circuit for the vertical magnet 20 at 38. Relay 11 also opens the circuit of release magnet 22 at 37.

The wire chief may now dial the first digit of 55 the number, which is the digit 2. Two interruptions are therefore produced in the bridge across the operating conductors 3 and 4, resulting in momentary deenergizations of the line relays 8 and 10. The operation of relay 8 is without effect at this time, but each time relay 10 falls back it sends an impulse to the vertical magnet 20, the circuit extending by way of 35, 38, off normal springs VON, winding of the slow acting 60 series relay 12, and winding of the vertical magnet 20 to battery. This circuit is altered at the vertical off normal springs in the well known manner at the first upward movement of the switch shaft, but is maintained by the operation 65 of relay 12 until the impulses cease. Two impulses are therefore delivered to the vertical magnet 20, which step the wipers 23-28 up two steps until they stand opposite the second level in their respective banks. The series relay 12 falls 70

back at the end of the impulses for the first digit, and transfers the impulsing circuit to the rotary magnet 21.

The wire chief may now dial the second digit 5 of the number, which is the digit 1. Accordingly, a single interruption is produced in the control circuit and the line relay 10 sends one impulse to the rotary magnet 21, the circuit extending from ground by way of 35, 38, off normal springs 10 VON, 43, 47, 55, 65, and winding of rotary magnet 21, to battery. The rotary magnet responds to the received impulses and rotates the wipers 23-28 one step, bringing them into engagement with the set of contacts in which is terminated the trunk comprising conductors 80-85. This trunk line, as previously explained, extends to a test connector selector in the local or No. 2 office.

The slow acting relay 16 is connected to the 20 impulse circuit in parallel with the rotary magnet 21, and therefore this relay responds to the impulse also. Upon energizing, relay 16 closes a circuit for the slow acting relay 17, the circuit extending from ground by way of 39, 54, 58, and 25 winding of relay 17, to battery. Upon energizing, relay 17 prepares a test circuit at 61 and prepares a circuit for relay 18 at 62. Shortly after the rotary movement has been completed, the slow acting relay 16 will fall back and break 30 the initial energizing circuit of relay 17. At the same time, however, the test circuit is completed over a path which extends from test wiper 28 by way of 64, 61, lower winding of test relay 15, and winding of relay 17, to battery. If the test 35 connector selector which has been selected by the test distributor is busy there will be a ground potential on the conductor 81, and accordingly the circuit just described will be completed, resulting in the operation of relay 15 and the 40 holding up of slow acting relay 17. Upon energizing, relay 15 opens the impulsing circuit at 55, opens the circuit of relay 18 at 54 to prevent this relay from pulling up, connects a source of busy signalling current to the operating conductor 4 at 56, and at 53 closes a circuit for the reversing relay 7. The latter relay, upon energizing, reverses the operating conductors 3 and 4 as regards their connections to the line relays 3 and 10, thereby reversing the direction of current flow over the operating conductors at the 50 test circuit. These operations result in giving the wire chief visual and audible busy signals, as is well known, and as is fully explained in the Crocker patent hereinbefore referred to.

55 Assuming now that the test connector selector which has been seized is idle, there will be no ground potential on conductor 81 and consequently when relay 16 falls back the test circuit will not be completed and relay 15 will not be energized. At the same time that relay 16 closes the test circuit, it also closes a circuit for relay 18 which extends from ground by way of 39, 54, 58, 62, and winding of relay 18, to battery. This circuit includes the contact 62 of 60 relay 17, which is maintained closed for an instant due to the fact that relay 17 is slow acting. Upon energizing, relay 18 locks itself at 66, opens the rotary magnet circuit at 65, and shifts the test wiper 24 to the upper winding of relay 15 65 at 64. Relay 18 also closes a bridge across the wipers 25 and 26 at 67, this bridge including the contact 36 on the line relay 10, which is now energized. Wipers 25 and 26 are now resting on the bank contacts to which operating conductors 70 75 82 and 83 are connected, and the bridging of

these wipers therefore closes the operating circuit over conductors 82 and 83 to the test connector selector. The line and release relays of the test connector selector accordingly pull up and prepare the switch for operation.

The wire chief may now dial the next digit 3 of the desired number. Three interruptions are accordingly produced in the circuit of line relay 10, which falls back three times and produces three interruptions of the bridge of wipers 25 and 26 at 36. These three interruptions cause deenergizations of the line relay of the test connector selector, and this switch is operated therefore in accordance with the digit 3 in order to select a test connector in the group in which the called subscriber's line is located.

While the third digit 3 is being repeated by the line relay 10 to the line relay of the test connector selector, the line relay 10 also sends impulses to the slow acting relay 16. Relay 16 accordingly responds and operates relay 17. Relays 16 and 17 are accordingly maintained energized during the dialling of the third digit and the latter relay holds the test conductors 5 and 6 open at 68 and 69.

If the operation of the test connector selector responsive to the third digit should result in the seizure of a busy test connector, the test connector selector will place a battery potential upon conductor 81, thereby closing a circuit for the test relay 15 of the test distributor TD. This operates relay 15 in order to give the wire chief a visual and audible signal in the manner hereinbefore explained.

Assuming, however, that the test conductor to which the connection has been extended is idle, no busy signal will be received and the wire chief will dial the fourth digit of the number, which is the digit 4, and also the fifth digit of the number, which is the digit 5. These two 40 digits are repeated by the line relay 10 in the same manner as has been described, and are effective to operate the test connector in its vertical and rotary movements in order to connect with the subscriber's line. The conditions 45 at this stage are that the test conductors 5 and 6 are extended by way of conductors 84 and 85 of the trunk to the test connector selector, and thence to the wipers of the test connector which are in connection with the subscriber's line. Also 50 the wiper 23 of the test distributor is extended over conductor 80 and the test connector selector to the test wiper of the test connector which is now in engagement with the test contact of the called line. During the repeating of the last 55 two digits the slow acting relays 16 and 17 of the test distributor respond as previously explained. Upon the falling back of relay 16 at the end of the last digit a test circuit is completed for testing the called line to determine 60 if it is busy or idle. This circuit extends from the test contact of the called line through the test wiper of the test connector and over the path just described including conductor 80, to wiper 23 of the test distributor, whence the 65 circuit extends by way of 63, 43, 60, 57, and the winding of the reversing relay 7 to battery. If the called subscriber's line is busy there will be a ground potential on the test contact and the circuit will be closed, resulting in the energization of relay 7. Relay 7 prepares a locking circuit for itself at 39 which is completed upon the falling back of relay 17, relay 7 being maintained over a path which includes wiper 23, 63, 43, contacts of relay 17 controlled by 60, 44, 30, 75

and winding of relay 7. Relay 7 is therefore held up as long as the called line continues its busy condition.

If the subscriber's line is idle when called, the 5 relay 7 will not be energized. With relay 7 de-energized, either due to having found the subscriber's line idle, or due to the subscriber's line having become idle after it was connected with, a circuit is completed over which ground is ex-10 tended to the test wiper of the test connector, this circuit extending from ground by way of 32, 30, 44, contacts of relay 17 controlled by 69, 43, 63, wiper 23, and conductor 89, whence the circuit continues through the test connector 15 selector to the test wiper of the test connector, as previously described. By means of this circuit ground is placed on the test contact of the called line, resulting in the energization of the bridge cut-off relay for the purpose of disconnecting the line relay. This clears the line of 20 its normal battery and ground connections so that the wire chief may now go ahead and perform the tests.

As mentioned hereinbefore, one of the tests 25 which the wire chief may desire to perform is the inward test, which requires the dropping back of the bridge cut-off relay of the subscriber's line. In order to deenergize the bridge cut-off relay, the wire chief will operate the B. C. O. key in 30 his test circuit. By the operation of this key the bridge across the operating conductors 3 and 4 is broken and ground is placed on conductor 3. This maintains line relay 10 energized and permits the line relay 8 to fall back. Relay 10 keeps the release relay 11 operated so that the distributor is not released, and relay 8 on falling back opens at 32 the circuit over which ground is supplied for holding the bridge cut-off relay of the subscriber's line. The bridge cut-off relay accordingly 35 falls back and the wire chief can proceed to make the desired test. After the test is finished the B. C. O. key may be restored and the bridge cut-off relay will pull up again.

If the wire chief desires to release the switches 40 beyond the test distributor TD while maintaining the distributor operated, he will actuate the connector release key labeled Conn. Release. This key breaks the loop and puts battery on conductor 4, resulting in the holding up of relay 8 and the falling back of relay 10. Relay 8 holds the release 45 11 energized, thereby preventing the release of the test distributor. On falling back, relay 10 breaks the bridge across the outgoing operating circuit at 36, which brings about the release of 50 the test connector and the test connector selector. The wire chief may then restore the connector release key and by further operation of the calling device he can reoperate the test connector selector and the test connector to set up a connection to another subscriber's line.

The test circuit TC is usually provided with a release key which will open the loop including the operating conductors 3 and 4 so as to release the entire connection without disconnecting the 55 test circuit from the test distributor. When the release key is operated, or when the test circuit is disconnected from the test distributor, the line relays 8 and 10 fall back, breaking the circuit of the release relay 11. The falling back of the line 60 relay 10 will break the outgoing operating circuit and release any switches that may have been set up beyond the test distributor. The falling back of the release relay 11 closes a circuit for release magnet 22, which restores the test distributor TD 65 to normal in the usual manner.

It will be assumed now that the wire chief desires to set up a connection to a subscriber's line in the No. 3 office. Assuming further that the test circuit TC is connected to the test distributor TD for this purpose, the line relays 8 and 10 are 70 energized as previously explained, followed by the energization of release relay 11. The wire chief may now dial the number of the subscriber's line, which will be assumed to be 34,567.

When the first digit 3 is dialled, the line relay 10 falls back three times and sends three impulses to the vertical magnet 20. The vertical magnet responds to these impulses and steps up the wipers 23-28 to the third level in their respective banks. The slow acting relay 12, in series with the vertical magnet 20, responds to these impulses also and holds up throughout the series of impulses, maintaining the vertical magnet circuit after the shifting of the vertical off normal springs VON. Relay 12 also closes a circuit at 41 75 for relay 19, which energizes. When the switch shaft reaches the third level, the shaft springs S are closed, whereupon a locking circuit is completed for relay 19, which extends from ground by way of 39, the right-hand pair of shaft springs S, 75, the interrupter contact of the rotary magnet 21, and winding of relay 19 to battery. It may be remarked that relay 19 is energized under control of relay 12 when the test distributor TD is used for setting up a connection local to the 80 No. 2 office, the same as it is in the present case, but since the shaft springs S are not closed on the second level, the relay 19 cannot lock itself and its temporary operation by relay 12 is without effect.

Shortly after the impulses for the first digit cease, the slow acting relay 12 will fall back, relay 19 remaining locked up. On deenergizing, relay 12 closes a circuit for relay 16 which extends from ground by way of 39, 41, the resistance 76, 74, and winding of relay 16, to battery. Resistance 76 is high enough so that the rotary magnet 21, in parallel with relay 16, is not operatively energized. Relay 16 energizes, however, and at 59 closes a circuit for relay 13, the circuit extending from ground by way of 39, 41, left-hand 85 pair of shaft springs S, 59, and winding of relay 13, to battery. On energizing, relay 13 locks itself over a circuit extending from ground by way of 39, 41, resistance 76, 43, and winding of relay 13 to battery. Relay 13 is the change-over relay, 90 which changes the test distributor TD from a two-digit switch to a one-digit switch and initiates its automatic hunting movement. A large number of circuit changes are brought about by the energization of relay 13 which can be more conveniently brought out in the discussion of the 95 ensuing operation.

With relays 13 and 16 energized as described in the foregoing, a circuit is completed for the rotary magnet 21 which extends from ground by way of 39, 41, left-hand pair of shaft springs S, 59, 49, 14, 65, and the winding of rotary magnet 21 to battery. The rotary magnet is energized over the above circuit and rotates the shaft one step, bringing the wipers 22-28 into engagement with 100 the first set of contacts in the third level. On energizing, the rotary magnet 21 also breaks the locking circuit of relay 19, which thereupon falls back and breaks the rotary magnet circuit at 74. The rotary magnet accordingly deenergizes and 105 closes its interrupter contacts. When relay 16 energized it operated relay 17 in the usual manner, so that at this juncture relays 16 and 17 will both be in energized condition. The breaking of the rotary magnet circuit at 74 also breaks the 110

circuit of relay 16, but this relay is slow acting and holds on for an instant. When the rotary magnet deenergizes and closes its interrupter contact, therefore, a new circuit is completed for relay 19, provided the trunk line terminating in the set of bank contacts engaged by the distributor wipers is busy. If this trunk line is busy there will be ground potential on test contact 71, and since contacts 71 and 70 are strapped together the ground potential will be picked up by wiper 23 which is now in engagement with contact 70. The circuit for energizing relay 19 therefore extends by way of 71, 70, 23, 63, 42 (relay 13 being energized), 60, 57, (relays 17 and 16 being energized), 45, rotary magnet interrupter contacts, and winding of relay 19 to battery. Relay 19 therefore again energizes and locks itself at 75, reclosing the rotary magnet circuit and the circuit of relay 16 at 74. Relays 16 and 17 are accordingly held energized and the rotary magnet is reoperated and advances the switch wipers another step. The operation of the rotary magnet again unlocks relay 19 and the same testing operation is performed again, relay 19 and the rotary magnet 21 operating alternately as long as the wipers of the distributor continue to find busy trunk lines.

It will be well to stop here for a moment and explain the wiring of the test contacts such as 70 and 71 which are associated with the group of trunk lines in the No. 3 office. These test contacts are connected together in pairs, except for the pair which is associated with the last trunk of the group. For instance, if there are four trunks in the group of test trunks extending to the No. 3 office, the test contacts 70 and 71 associated with the first trunk line in the group are strapped together as shown in the drawing, as are also the pairs of test contacts which are associated with the second and third trunks. The pair of test contacts associated with the fourth trunk, which is the last trunk line of the group, are left unstrapped. This arrangement is similar to the arrangement which is in common use with rotary connectors.

Assuming now that all of the trunk lines are busy, the fourth operation of the rotary magnet 21 will set the distributor wipers 23-28 on the fourth set of bank contacts and will bring about the deenergization of relay 19. The fourth trunk line being busy, according to the assumption, there will be a ground on the fourth test contact corresponding to test contact 71, but since this test contact is not strapped to the paired test contact corresponding to the contact 70 there will be no circuit closed for reoperating relay 19. The rotary magnet accordingly is not reoperated and shortly the slow acting relay 16 will fall back. The falling back of relay 16 closes a circuit for the test relay 15 in series with the slow acting relay 17, the circuit extending from the grounded test contact engaged by wiper 24, by way of said wiper 24, 64, 61, winding of relay 15, contacts controlled by 58, and winding of relay 17, to battery. Relay 15 accordingly energizes and relay 17 is maintained energized. Thus the busy signal is transmitted to the wire chief in the manner previously explained.

Assuming now that an idle trunk line is found, which may be the trunk line 86-89, shown in the drawing, when the rotary magnet 21 falls back after bringing the wipers into engagement with the set of bank contacts in which this trunk line terminates, it closes the circuit of relay 19 as previously explained, but this relay does not en-

ergize because although the test contacts 70-71 are strapped together there is no ground potential on test contact 71. The rotary magnet circuit is not again closed, therefore, and the slow-acting relay 16 falls back. On deenergizing, relay 16 closes a test circuit which includes relay 15, as previously explained, and also closes a circuit for relay 18, the slow acting relay 17 remaining momentarily in operated condition. Since there is no ground on the test contact 71, the test relay 15 will not energize, contact 54 remains closed, and relay 18 is permitted to energize. This relay locks itself at 66. In energized position, relay 18 connects ground to the test wiper 24, the circuit extending from ground by way of 43 and 64 to the wiper 24. This operation places ground on test contact 71 and marks the trunk line busy to other test distributors. Relay 18 also closes the outgoing operating circuit at 67.

The connection has now been extended to the No. 3 office. The trunk line 86-89 terminates in that office in a test distributor, which may be the same as test distributor TD. Assuming that such is the case, when the bridge is closed across the wipers 25 and 26, by operation of relay 18, the operating circuit over conductors 86 and 87 is completed, and the line relays such as 8 and 10 of the test distributor will pull up, preparing it for operation in the manner described in connection with test distributor TD. It will be understood also that the test leads 5 and 6 now extend by way of wipers 27 and 28 and outgoing test conductors 88 and 89 to a pair of incoming test conductors associated with the test distributor in the No. 3 office, these test conductors corresponding to the test conductors 5 and 6 of the test distributor TD.

The wire chief may now proceed to dial the remaining digits of the subscriber's number, which are repeated over the outgoing operating circuit comprising conductors 86 and 87 by the line relay 10 at contact 36. The second and third digits are effective to control the operation of the test distributor in the distant No. 3 office, which accordingly extends the connection to a test connector in the desired group. The fourth and fifth digits are effective to control the operation of the test connector to complete the connection to the subscriber's line.

It will be observed that since the change-over relay 13 is in energized condition while the digits are being repeated to the distant office, the local impulse circuit in the test distributor TD is broken at 41, so that relays 16 and 17 do not respond.

It will be observed also that since the change-over relay 13 is in energized position, the control circuit extending to the distant office includes the lower winding of the electro-polarized relay 14, the shunt being removed from the lower winding of this relay at 50. Relay 14 is an electro-polarized relay of the usual type having an upper polarizing winding which is maintained energized at 39 and having a low resistance winding included in one side of the control circuit. When the current flow in the control circuit is in the normal direction, as it is during the setting up of the connection, the two windings of relay 14 oppose each other and the relay does not energize. If a busy condition should be encountered in the No. 3 office while the connection is being set up, it will be understood that a busy tone will be placed on the operating conductor 87 at the test distributor and at the same time the current flow over the operating conductors 86 and 87 will

be reversed. This reversal of current in the control circuit causes the electro-polarized relay 14 at the distributor TD to operate. Relay TD connects a condenser between the operating conductor 4 and the outgoing operating conductor 87, so that the busy tone can get back, and also closes a circuit for the reversing relay 7 at 51. Thus the busy signals are relayed back from the test distributor in the distant office through the 10 test distributor TD to the test circuit TC.

It should be explained also at this time that with the relay 13 in energized condition the short circuit which normally exists around the lower winding of relay 9 is broken and one terminal of 15 this winding is connected to battery through a resistance 71. This change in the circuit of relay 9 has for its object the preparing of this relay for operation by the deenergization of either relay 8 or relay 10, as will be explained hereinafter. 20 In the meantime it may be pointed out that when both these relays fall back together, as during the transmission of impulses, relay 9 does not operate. In order to take care of the contingency that the relays 8 and 10 may not deenergize exactly together relay 9 is provided with a normally short circuited upper winding which makes it very slightly slow to operate.

The connection to the subscriber's line in the distant office having been established, it will be 30 assumed that the wire chief proceeds to make some tests. If the wire chief desires to drop back the bridge cut-off relay of the called line, he will operate the B. C. O. key in the test circuit TC. The actuation of this key opens the bridge across 35 the operating conductors 3 and 4 and grounds the conductor 3, which allows relay 8 to fall back and holds up relay 10. Relay 10, of course, maintains the release relay 11 energized. As soon as relay 8 falls back relay 9 operates over a circuit which extends from ground by way of 35, lower winding of relay 9, 49, and resistance 71 to battery. On energizing, relay 9 breaks the bridge across the outgoing control circuit including conductors 86 and 87 at 33 and also, relay 8 being back, connects ground to conductor 86, the circuit extending from ground by way of 31, 33, 36, 40 45, 67, and through wiper 25 and contact engaged thereby to conductor 86. Thus it will be seen that the same condition that is imposed on the control circuit incoming to the test distributor TD is imposed on the outgoing control circuit comprising conductors 86 and 87 extending to the test distributor in the distant office. At the distant office the test distributor of course responds to this control condition in the same way 50 that was described in connection with the test distributor TD in the establishment of a local connection, and the result is that ground is removed from the circuit of the bridge cut-off relay of the subscriber's line and this relay is allowed to deenergize. The circuit changes described endure only as long as the B. C. O. key remains actuated, and when this key is restored the circuits resume their normal condition.

Assuming now that the wire chief desires to 65 release the test connector in the distant No. 3 office, he will operate the connector release key in the test circuit TC. By the operation of this key the bridge across the operating conductors 3 and 4 is broken and battery is placed on conductor 4. The result is that relay 8 is held up while relay 10 is allowed to fall back. As soon as relay 10 falls back relay 9 is energized over a circuit which extends from ground at 31 by 70 way of the lower winding of relay 9 and through 75

the winding of the release relay 11 to battery. Thus relay 9 is energized and at the same time the release relay 11 is maintained operated. With relay 10 deenergized and relay 9 energized it will be seen that the bridge across the outgoing control circuit is broken at 36, while at the same time battery is placed on the lower side of the control circuit at 34. Thus the condition imposed on the conductors 3 and 4 incoming to the test distributor TD is relayed or repeated at the test distributor and is imposed in turn on the operating conductors 86 and 87 extending to the test distributor in the distant No. 3 office. As a result the line relay in the distant test distributor which corresponds to the line relay 10 of the test distributor TD is permitted to fall back, while the other line relay, corresponding to the line relay 8, is held energized. The control circuit extending to the test connector is thereby broken and the test connector is released.

In connection with the foregoing explanation of the operation of the test distributor in the distant office, it will be understood that on all levels in which these test distributors have access to test connectors the shaft springs such as S do not close and consequently the test distributors operate as two-digit switches. Under these conditions relays such as 13 and 9 are never energized. If the test distributor in the distant office should have access on some level to outgoing trunks extending to another office then of course the shaft springs of the test distributor in the No. 3 office are adjusted so that on this particular level they will close. It follows that the control conditions relayed from the test distributor TD in the No 2 office would be relayed a second time through the test distributor in the No. 3 office in the event that such latter test distributor had been operated to select a trunk 40 to another office.

The invention having been described that which is believed to be new and for which the protection of Letters Patent is desired will be pointed out in the appended claims.

What is claimed is:

1. In combination, a test distributor, a local test trunk and an inter-office test trunk accessible to said distributor, a test trunk incoming to said distributor, means for controlling said distributor over said incoming trunk to connect with either said local or inter-office trunk, means for bridging two conductors of the connected trunk in either case, means responsive to a control condition imposed on the incoming trunk for opening the bridge if the connected trunk is the local trunk, and means responsive to the same control condition for connecting one pole of the exchange battery to one of the bridged conductors and for opening the bridge if the connected 55 trunk is an inter-office trunk.

2. In combination, a test distributor, a test trunk, means for operating said distributor to connect with said test trunk, means in the distributor for closing a bridge across two conductors of said trunk, and means in said distributor for opening said bridge and for connecting one pole of the exchange battery to one of said conductors.

3. In combination, a test distributor, a test 70 trunk, means for operating said distributor to connect with said test trunk, means in the distributor for closing a bridge across two conductors of said trunk, and means in said distributor variably operable to connect one pole of the ex- 75

change battery to one of said conductors or the other pole of battery to the other of said conductors and to open said bridge.

4. In combination, a test distributor, a test trunk incoming to said distributor, two outgoing test trunks accessible to said distributor, means for controlling the distributor over said incoming trunk to connect with either of said outgoing trunks, means for imposing a control condition on said incoming trunk, and means in said distributor for repeating said control condition in two different ways depending on which of said outgoing trunks has been connected with.

5. In combination, a test distributor, a test trunk incoming to said distributor, two outgoing test trunks accessible to said distributor, means for controlling the distributor over said incoming trunk to connect with either of said outgoing trunks, means for imposing a control condition on said incoming trunk, means in said distributor for exactly reproducing the control condition in the connected outgoing trunk if one of said outgoing trunks has been connected with, and means for converting said control condition into a different control condition in the connected outgoing trunk if the other outgoing trunk has been connected with.

6. In a test distributor, two line relays, means for operating said distributor under control of said relays, a relay cooperating with said line relays for repeating control conditions, and means actuated responsive to a particular operation of said distributor for rendering said last mentioned relay responsive to the deenergization of either line relay while the other is held energized.

7. In an automatic switch, two line relays, a control relay, and two circuits for said control relay controlled by said line relays, respectively, said control relay being short circuited when both of said circuits are closed and operative over the other circuit when either circuit is opened.

8. In a telephone system, a test distributor, local test trunks accessible to said distributor and extending to switches of a test train in the same office, a group of inter-office test trunks accessible to said distributor and extending to another office, means for operating said distributor responsive to two digits to select one of said local test trunks or for operating the same responsive to a single digit to select the group of inter-office test trunks, and means responsive to the selection of said group for automatically operating the distributor to select an idle trunk of the group.

9. In a telephone system, a test distributor, local and inter-office test trunks accessible to

said distributor, means for operating said distributor responsive to two digits or a single digit depending on whether a local or inter-office trunk is to be connected with, and means effective when either connection is completed for conditioning said distributor to repeat impulses over the connected trunk. 5

10. In a telephone system, a test distributor, means in said distributor normally effective for operating the same responsive to two successive 10 digits, a changeover relay in said distributor for altering the circuits thereof to provide for a hunting movement following an operation responsive to a single digit, a relay responsive to the first digit, and means including said relay 15 and shaft springs cooperating therewith if the first digit has a particular value for operating said changeover relay.

11. In a telephone system, a test distributor, an incoming test trunk, an outgoing test trunk, 20 means for controlling said distributor over said incoming trunk to connect with said outgoing trunk, means in said distributor for bridging two conductors of said outgoing trunk, a polarized relay included in said bridge, and means 25 controlled by said relay for establishing an inductive connection between a conductor of said outgoing test trunk and a conductor of said incoming test trunk so as to pass tone currents applied to the outgoing trunk back through the 30 distributor to the incoming trunk.

12. In a telephone system, a test distributor, an incoming test trunk, an outgoing test trunk, means for controlling said distributor over said incoming trunk to connect with said outgoing 35 trunk, means in said distributor for bridging two conductors of said outgoing trunk, a polarized relay included in said bridge, a relay for reversing the current flow in two conductors of said incoming trunk, and a circuit for said reversing 40 relay controlled by said polarized relay.

13. In an automatic switch having a hunting movement, a stepping magnet for operating the switch in its hunting movement, a slow acting control relay, a circuit for energizing said relay and magnet in parallel, means for first closing said circuit through a resistance which is too high to permit operation of said magnet but low enough to permit operation of said relay, and means responsive to the operation of said relay for closing said circuit over a path which excludes said resistance, thereby operating said magnet. 45 50 55
